TORCH HEAD SAFETY FLASHLIGHT

Arthur H. Moore, Fairfield, Conn., assignor to The Bridgeport Metal Goods Manufacturing Company, Bridgeport, Conn., a corporation of Connecticut

Application December 27, 1954, Serial No. 33,693

Term of patent 14 years

(Cl. D48—24)

Fig. 1.

Fig. 2.

Fig. 3.

Fig. 4.

Fig. 1 is a side view of a torch head safety flashlight, showing my new design;

Fig. 2 is an end view thereof;

Fig. 3 is a section substantially on line 3—3 of Fig. 2, and

Fig. 4 is a section substantially on line 4—4 of Fig. 3.

The predominant features of the design are in the head portion of the flashlight as shown in full lines.

I claim:

The ornamental design for a torch head safety flashlight, substantially as shown and described.
